UNITED STATES PATENT OFFICE.

NILS H. ANDERSON, OF MIDDLETOWN, CONNECTICUT, ASSIGNOR OF ONE-HALF TO
WILLIAM A. LORENZ, OF HARTFORD, CONNECTICUT.

SOUND AND SHOCK ABSORBING FOOT.

REISSUED

1,214,256.

Specification of Letters Patent. Patented Jan. 30, 1917.

Application filed June 10, 1914. Serial No. 844,225.

To all whom it may concern:

Be it known that I, NILS H. ANDERSON, citizen of the United States, and resident of Middletown, in the county of Middlesex and 5 State of Connecticut, have invented certain new and useful Improvements in Sound and Shock Absorbing Feet, of which the following is a specification.

This invention relates to new and useful 10 improvements in feet or supports for type-writing machines, and refers particularly to sound and shock absorber feet for typewriters, calculating machines and the like.

The object of the invention is to provide 15 an improved form of sound and shock absorbing feet which may be attached to any of the wellknown makes of writing machines and so as to support the machine upon either a stationary or folding desk; to design the 20 device so it will serve to support the machine in different positions; further to eliminate the use of springs, to include a rubber cushion and an inclosing case for the same whereby said cushion cannot flatten out and 25 become rigid, and finally to arrange and design the device in a simple, practical and inexpensive manner.

With the above and other objects in view 30 my invention resides and consists in the novel provisions, combination and arrangement of parts, shown upon the accompanying drawings forming a part of this specification, upon which similar characters of reference denote like or corresponding parts 35 throughout the several figures and of which,

Figure 1 shows a central vertical sectional elevation of my improved typewriter foot, shown attached to the frame of a writing machine. Fig. 2 shows a detached side view 40 of three of the parts of the foot assembled, but not connected with the writing machine frame. Fig. 3 is a detached side elevation of the part of the support which is attached to the writing machine frame and which in 45 turn carries the other parts of the device. Fig. 4 shows a similar detached side view of the cushion or rubber part of the support shown in Figs. 1 and 2 and Fig. 5 shows a central vertical sectional elevation of a metal 50 socket adapted for attachment to a desk cover and in which my improved machine foot may be seated.

Referring in detail to the characters of reference marked upon the drawings 10 rep-

resents a portion of the frame of a writing 55 machine and 11 is a threaded socket in the under side of the same. The frame may obviously be of any of the well known types of machine frames, while the threaded hole would have to be special to receive the attachable part of the foot. This support, or 60 foot, proper is formed in four parts, and one of these parts, viz: the lower sheet metal inclosing cap, would vary slightly in construction according to the particular conditions 65 under which the device is to be used, as will later be more fully explained. The main part of the leg 12 of the foot is clearly shown in Figs. 1 and 3 and as will be noted includes a reduced threaded upper end portion 12^a, 70 an intermediate and similar larger body portion 12^b, an annular flange portion 12^c and a tapered lower end portion 12^d. I also preferably include a hole 13 in the body portion 75 of the leg to receive a suitable tool or instrument for screwing the leg into the threaded hole of the machine frame, as in the attachment of the foot to a machine.

The shell 14 is provided with a suitable hole 15 through which the intermediate portion 12^b of the foot passes. Said parts are thus connected before the leg is attached to a machine. The lower portion of this shell is somewhat larger than the upper portion and its peripheral face is threaded, as at 16, 80 to receive the cap 17 which like the upper shell is provided with a hole therethrough to accommodate the outer extended portion 18 of the cushion pad 19 and which as before stated is preferably formed of rubber. This 85 pad is made of a size and shape to loosely fit into the lower portion of the inclosure shell and cap, and includes a central pocket 20 to receive the reduced end of the leg and an annular rib 21 to be engaged by the two shell 90 members, as shown in Fig. 1.

When the support is used upon a stationary table it is preferably constructed in the manner indicated in Fig. 1 so that the lower end of the rubber pad is exposed for 100 engagement with the table. On the other hand, if it is to be used in connection with a folding desk where the cover may be tilted and closed in, I would preferably employ a cap 17^a like that shown in Fig. 5, and 105 which like the cap 17 is threadably attached to the upper shell 14. The hole through this shell 17^a serves to receive an attaching bolt

or screw 22 which as shown in Fig. 5 would pass into and preferably through the top 23 of the desk.

From the foregoing it will be noted that 5 the foot is adapted for attachment to most any form of machine in which a suitable threaded hole may be formed, and that when so attached it may be made to become part of the machine, as shown in Fig. 1. When 10 the foot is to be secured to the table in the manner referred to in Figs. 2 and 5 the leg is first attached to the machine and then to the top of the table by turning the shell 14 and running its thread into the thread of 15 the shell 17^a so as to secure the support and machine to the said desk top. When inclosed in either manner a suitable and desirable form of cushion support is formed, so that the fixed and metal inclosing parts 20 of the rubber pad do not come in contact with the metal leg, and the latter is supported wholly and entirely upon the cushion, which insures a soft and yielding support. The inclosing of the rubber serves to prevent 25 it from drying out and further holds it in shape, thus prolonging its life and usefulness.

Having thus described my invention what I claim and desire to secure by Letters Patent is:—

- 30 1. A sound eliminating and shock absorbing support for a writing machine, consisting of a rubber cushion, an attachment stud with its lower end resting upon said cushion 35 and its upper end adapted to be secured to the machine to be supported, a shell surrounding said cushion and loosely connected with said stud, and a cap secured to said shell and holding the rubber cushion therein.
- 40 2. A sound eliminating and shock absorbing support for a writing machine consisting of a cushioning pad, an attachment stud with one end resting upon said pad and the other end adapted to be secured to the machine to be supported, a shell surrounding 45

said pad and loosely connected with said stud, and a cap secured to said shell and holding the pad therein, said cap having an opening in its lower end through which the lower end of the pad projects.

50 3. A sound eliminating and shock absorbing support for a writing machine, consisting of a rubber cushion, having a pocket in its upper face, an attachment stud with its lower end loosely fitting the pocket in the 55 cushion, and its upper end adapted to be secured to the machine to be supported, a shell surrounding said cushion and loosely fitted upon the supporting stud, and a cap secured to the shell and holding the rubber 60 cushion therein.

65 4. A sound eliminating and shock absorbing support for a writing machine consisting of an attachment stud having a threaded upper end and a tapered lower end, a shell movably secured to said stud, a perforated cap secured upon the lower end of the shell, and a cushion pad fitting within and held in the shell by said cap, said pad having a tapering recess in its upper end fitting the 70 lower end of the attachment stud, and its lower end projecting through said cap.

75 5. A sound eliminating and shock absorbing support for a writing machine consisting of an attachment stud, having a threaded upper end, a reduced lower end, and an annular flange intermediate the ends, a shell loosely fitted upon said stud above the flange, a perforated cap secured upon the lower end of the shell, and a cushion pad held 80 within the shell by said cap, and having its upper end supporting the stud, and its lower end projecting through the cap.

85 Signed at East Hampton, in the county of Middlesex and State of Connecticut this 5th day of June A. D., 1914.

NILS H. ANDERSON.
